Filed Mar. 1, 1962, Ser. No. 69,033

Term of patent 7 years

(Cl. D7—7)

The figure on the drawing is a perspective view of a shoe or similar article showing my new design. The opposite side is substantially the same as that shown.

The dominant feature of my design resides in the portions shown in solid lines.

I claim:

The ornamental design for a shoe or similar article, substantially as shown and described.
